UNITED STATES PATENT OFFICE

2,389,220

SWITCH ACTUATOR

Earl W. Tredeau, West Allis, Wis.

Application November 20, 1942, Serial No. 466,306

2 Claims. (Cl. 200—172)

This invention relates to switch actuators and more particularly to an actuator to enable a child to operate a standard light switch.

In the home, light switches are placed in the wall at an elevation which is convenient for adults. Small children, so called toddlers, therefore can not reach the switch to turn on the light and as a result are likely to trip and fall in the dark.

One object of the present invention is to provide a switch actuator applicable to a standard wall light switch to enable a small child to operate the switch.

Another object is to provide a switch actuator which is readily applied to the face plate of a standard wall switch, and which will be simple to use and economical to manufacture.

Further objects will become apparent upon considering the following specification, which, when taken in connection with the accompanying drawing illustrates two forms of the invention.

In the drawing:

Fig. 1 is a front elevational view of an ordinary lever action snap switch used in home lighting circuits, showing the actuator comprising the present invention in place thereon;

Fig. 2 is a view partly in cross-section on the line 2—2 of Fig. 1 showing details of the actuator;

Fig. 3 is a front elevational view of a push button type of domestic light switch, showing a modified form of actuator included in the present invention in place thereon;

Fig. 4 is a view partly in cross-section taken on the line 4—4 of Fig. 3 showing the modified form of actuator; and

Fig. 5 is a cross-section on the line 5—5 of Fig. 4 showing the modified form of actuator.

Referring first to Figs. 1 and 2 which show a lever type of home lighting switch 10 mounted in a wall box 11. The switch 10 has a retaining piece 12 secured on the outer edge thereof which positions the switch 10 in the box 11, by means of screws 13 which pass through the outer ends of the retaining piece 12 and are secured in the rim of the box 11.

A face plate 14 covers the open end of the switch 10 and fits flush on the wall 15. The face plate 14 is normally secured in position by means of screws 16 which pass through the face plate 14 and engage threaded holes in the retaining piece 12. In a standard switch the screws having flat heads fit into countersunk recesses in the plate 14. In this invention these screws are re-

placed by longer screws 16 having heads with a flat rear face, such as round head screws.

The switch has an actuating lever 17 which projects through the face plate and moves on a pivot to an "on" position and an "off" position.

The secondary actuator which forms the subject matter of the present invention comprises a plate 20 having an aperture 21 therein which receives the switch lever 17, and a pair of spaced aligned apertures 22, 22 through which the screws 16 pass. The plate 20 is held spaced from the face plate 14 by spacer sleeves 24—24 against which the plate 20 abuts and which have reduced ends 25 extending through the apertures 22—22 against which the screws 16 abut, to give free rectilinear movement to the plate 20 while clamping the face plate 14 securely in place.

A stick 26 or other compression resisting member is loosely secured on a pivot 27 to the lower end of the plate 20 and extends downwardly to a point within the easy reach of a small child.

To operate the light switch a child wishing to turn on the light grasps the stick 26 and moves it either up or down. The movement of the stick 26 is transmitted to the plate 20 which moves up or down guided by the screws 16. The edges of the aperture 21 engage the switch lever 17 to transmit the motion of the plate 20 to the lever 17 and actuate the switch.

In the form of the invention shown in Figs. 3, 4 and 5, for use with the push button type of switch, a plate 30 is secured to the face plate 14 by the screws 16'. The plate 30 has ears 31 which turn outwardly and pivotally receive an actuating lever 32. The actuating lever has arms 33—33 which engage the two buttons 34—34 of the conventional push button switch. A stick or other compression resisting member 35 is pivotally attached to the outer end of the lever 32 on a pin 36.

To operate the light switch a child grasps the stick 35 and by moving it up or down causes the lever 32 to rotate on its pivot 37 which causes the arms 33—33 to press one of the buttons 34 to actuate the switch.

It will be noted that in both forms of the invention the screws 16' serve to secure both plates 20—30 and the face plates 14—14 in position and that the screws 16' pass through the holes provided in the standard switch for securing the face plates.

Having thus described the invention it is realized that it is susceptible to various changes and modifications and it is not therefore desired to limit the invention to the precise forms herein

shown and described but only by the scope of the appended claims.

What is claimed as new and desired to secure by Letters Patent is:

1. For a light switch having a retaining strip with a pair of spaced threaded holes therein, a face plate having apertures therethrough in alignment with said threaded holes and a primary switch actuator projecting through said face plate, a secondary actuator structure adapted to be mounted on the switch without removing or reversing said face plate comprising a secondary actuator having elongated apertures therein and an aperture receiving said primary switch, spacing means projecting through said elongated apertures and forming guides for said secondary actuator, a pair of screws for securing said spacing means against said face plate and the face plate in assembled position and passing through the apertures in said face plate and the threaded holes of said strip, and means on said secondary actuator to enable the primary switch actuator to be moved from a point remote therefrom and within the reach of a toddler.

2. For a light switch having a retaining strip

with a pair of spaced threaded holes therein, a face plate having apertures therethrough in alignment with said threaded holes, and a primary switch actuator projecting through said face plate, a secondary actuator structure adapted to be mounted on the switch without removing or reversing said face plate comprising an actuator member having spaced slots therein and an aperture receiving said primary switch actuator, a pair of apertured spacers having reduced portions projecting through said slots to guide said secondary actuator, a pair of screws having heads engaging the reduced ends of said spacers and passing through the apertures in said spacers and said face plate and into said threaded holes to clamp said spacers against the face plate and the face plate in assembled position, said actuator member being loosely mounted between said spacers and the heads of said screws, said actuator member having an extension to enable the primary switch actuator to be moved from a point remote therefrom and within the reach of a toddler.

EARL W. TREDEAU.
